[57] CLAIM

The ornamental design for a bathing enclosure shell, as shown and described.

DESCRIPTION

FIG. 1 is a right front perspective view of a bathing enclosure shell showing my new design;

FIG. 2 is a top plan view thereof;

FIG. 3 is a front elevational view thereof;

FIG. 4 is a cross sectional view taken on line 4—4 of FIG. 3;

FIG. 5 is a cross sectional view taken on line 5—5 of FIG. 3;

FIG. 6 is a cross sectional view taken on line 6—6 of FIG. 2;

FIG. 7 is a cross sectional view taken on line 7—7 of FIG. 3;

FIG. 8 is a cross sectional view taken on line 8—8 of FIG. 3;

FIG. 9 is a rear elevational view thereof;

FIG. 10 is a bottom plan view thereof;

FIG. 11 is a left side elevational view thereof; and

FIG. 12 is a right side elevational view thereof; and

FIG. 13 is a frontal perspective view of an alternative embodiment of my bathing enclosure shell, taken from the left front corner; the enclosure being the mirror image of that of FIG. 1 along plane 7—7 of FIG. 4. The fragmentary broken line representation of a bathroom wall in FIG. 1 and the broken line showing of openings in FIGS. 4, 6, and 8 are for purposes of illustration only and form no part of the claimed design.
